(57) **CLAIM**

The ornamental design for a combined cigar and club holder, as shown.

DESCRIPTION

FIG. 1 illustrates a perspective overview of a combined cigar and club holder;

FIG. 2 illustrates an elevated front side view thereof;

FIG. 3 illustrates an elevated side view thereof;

FIG. 4 illustrates a perspective lower side view thereof;

FIG. 5 illustrates an elevated top side view thereof;

FIG. 6 illustrates an elevated bottom side view thereof;

FIG. 7 illustrates a perspective overview thereof; and,

FIG. 8 illustrates an elevated front side view thereof.

The broken lines shown in FIGS. 7 and 8 are for environmental purposes only and form no part of the claimed design.
